UNITED STATES PATENT OFFICE.

BURNHAM C. STICKNEY, OF RUTHERFORD, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed May 3, 1924. Serial No. 710,768.

This invention relates to the revoluble platens of typewriting machines, in which type-bars swing against the work-sheet placed upon the platen.

5 One of the objects of the invention is to improve the construction of the platen, with a view to securing clearness of the type-impressions, and with a view to reducing the noise of the type blows upon the work-sheet, 10 and also to enable clear impressions to be made by light finger strokes upon the keys. Another feature of the invention is that it is rendered practicable to eliminate the noisy and otherwise objectionable anvil, abutment 15 or stop-ring against which it has long been the practice for the type-bars to strike in Underwood and other machines, said anvil or stop-ring being usually placed near the pivots of the type-bars and being struck by 20 the type-bars when the latter approach printing positions. The type-bars then usually spring until the types strike the work-sheet, as disclosed in the Manning Patent No. 612,858, dated October 25, 1898.

25 Other features and advantages will hereinafter appear.

In the accompanying drawings.

Figure 1 is a sectional elevation on an enlarged scale of one form of revoluble platen 30 embodying the present improvements.

Figure 2 is a perspective diagrammatic view to illustrate the manner of supporting the platen-body upon a platen-axle.

Figure 3 is a diagram to illustrate one 35 kind of joint or seam for the outer covering or skin of the platen.

Figure 4 is a sectional elevation of the type-bar system and segment of the Underwood typewriting machine, showing the improved platen. At this figure there is also shown an improved manner of supporting the hub ends of the detachable type-bars against shaking when in printing positions.

Figure 5 is a diagram of the platen, showing one manner of winding an outside skin or layer thereon.

The weighted body of the platen is preferably in the form of a length of heavy, plastic metal tube 10, the wall of which may 50 be about 1/8 of an inch thick; and the diameter of the pipe or tube may be nearly the full diameter of the finished platen. This body may consist of a length or section of commercial lead pipe, such as ordi-

narily used by plumbers and others. The 55 length of the lead body may equal the length of the platen; and it may be supported at its ends upon soft rubber ends, bushings or disks 11, so as to prevent transmission of noise vibrations from the lead body to the 60 platen-axle 14. These soft rubber ends or heads may be fitted upon bosses or hubs 12, secured by screws 13 upon the platen-axle 14. In order to lock the platen and the axle 65 for rotation together, spurs or teeth 15 may radiate from the bosses into radial holes 16 in the soft rubber ends 11, so that said ends must rotate with the bosses or hubs 12. From the soft rubber ends may project integral soft rubber hobs or teeth 17, to fit into 70 notches 18 cut in the ends of the lead body. The latter is thus firmly supported upon the platen-axle, and the latter is enabled to drive the platen.

The rubber platen ends may also be perforated at 19 to make a more springy support for the platen-body, thus conducing further to quietness of operation; the weight and inertia of the platen making a rigid support unnecessary.

75 One of the chief characteristics of the lead body is its weight, so that the lead pipe becomes something having the nature of an anvil, to coact with the types to produce the impressions upon the work-sheet. The type 80 delivers a quick blow upon the paper, and the blow is resisted by the lead body because of its relatively great weight and inertia. The excellence of this backing is derived partly from its quality of withstanding the 85 sharp blows of the type. The speed of the type is so great that the lead body cannot be started so quickly into bodily motion, and hence it does not yield under the blows. In other words, the inertia of the heavy platen 90 is an element in producing the necessary resistance to the type blows, so that the paper and ribbon upon one side are subjected to hard blows, and upon the other side meet with a resisting body, thus enabling 95 heavy impressions to be made upon the paper by light key strokes, thereby conducing to ease of operation, as well as quietness.

100 Moreover, the lead itself is not only heavy, but has such a plastic nature as to make it practically a perfect medium for serving as a backing for the sheet when receiving the

type-impressions. The substantial inelasticity of the lead, combined with its plastic or semi-plastic quality, makes it an excellent device or contributory element for securing clear type-impressions through the ink ribbon 20 upon the paper.

Another feature of the invention is that by the use of a lead tubular body, the noise of the type blows is remarkably reduced, 10 while conferring the advantages above mentioned.

While in some cases the lead body may be lined with a thin shell of steel, brass or the like to give rigidity, still for general use 15 the lead body may be unprovided with such stiffening shell, as said lead body may be sufficiently thick and stiff of itself as not to be liable to become bent or warped by the impact of the types. Great stiffness is not 20 required in a platen, since when in place in the machine, it is not exposed to such rough usage as would be liable to bend it. Thus, although the lead body is preferably bendable when great force is applied thereto, 25 this is not objectionable in practice.

Upon the lead body there is preferably stretched one or more windings of thin highly elastic soft rubber sheeting 21, which may be wound from a web whose width 30 equals the length of the platen. This may consist of one or more layers of dental rubber, and is preferably permanently under high tension, so as to provide a rather hard wrapping, which nevertheless is highly 35 elastic. This elastic rubber layer is an excellent contributory element for aiding the lead body in securing sharpness of the type-impressions; the rubber, with its overwound paper layer (hereinafter mentioned) forming 40 an excellent combination for this purpose; and the rubber also aids in protecting the lead from being dented by the type blows. Moreover the rubber layer conduces to quietness of operation.

45 The rubber layer or jacket may be in the form of rubber bands, which are originally of small diameter or undersized, and are stretched out and placed side by side at 21^a upon the lead body, to form the rubber layer.

50 The impression-clearing quality of the rubber layer may be well brought out by winding thereover several layers of thin manila paper 23 or other extremely tough paper. The rubber backing 21 under said 55 paper layers makes a combination which gives remarkable clearness of printing, especially when backed up by the lead body 10. The paper may be wound tightly, and secured by cement.

60 To complete the platen there is preferably used a protective skin or layer of tough material, which may be for example in the nature of gold-beaters' skin; or gut may be used. It preferably consists of a hard, 65 tough quality of kangaroo skin, which is a

well-known tanned article of commerce, and is commonly used in making kid shoes and various other articles. Its toughness gives it the requisite durability, and enables it to withstand the blows of the types indefinitely. While it is not cut by the types, it is sufficiently flexible to make an excellent backing for the sheet, and conduces to quietness of operation, and aids efficiently in rendering the type-impressions clear.

70 The kangaroo skin, the paper and the rubber in combination have the effect of substantially preventing indentation of the lead by the types, especially when the keys are struck lightly. It is one of the advantages 75 of the invention that light blows of the types make clearly-inked type-impressions, whereby quietness as well as ease of operation is attained. The use of this platen, on account of its excellent impression qualities, 80 permits the use of a light or reduced-width type-bar as seen at 24, conducing to ease of key touch. The thin rubber sheeting may be interwound with single or doubled (two-ply) 85 windings of paper, if desired, to make up a 90 combined rubber and paper element.

95 Thus it will be seen that there is a resisting but highly elastic and impression-clearing layer, whose qualities are well developed by the overlying windings of paper, preferably tough and thin, while the paper is 100 protected by the tough leather or skin facing, and the three elements together protect the lead from hammering of the types, without impairing the efficiency of the lead 105 in securing quietness of work and clearness of type-impressions.

110 The winding of highly tensioned rubber-sheeting, which may be two or three layers (or the rubber bands), may amount to about 105 1/64 of an inch more or less, although this may be increased in some cases to 1/32 of an inch. The winding of tensioned paper may comprise three to six layers of thin manila or other very tough paper, these 110 paper windings amounting to about 1/100 of an inch more or less; although this may be increased in some cases. The facing of kangaroo skin (or other leather or the like) 115 may be about 1/64 of an inch thick, or in some cases 1/32 or somewhat more, depending partly upon its softness or hardness, and partly upon the number of carbon copies which it is desired to make. If gold-beaters' skin or gut is used, there may be several 120 windings, all of which may be under tension; and such windings may aggregate 1/64 to 1/32 of an inch in thickness. The external diameter of the platen is about 1 3/4 inches.

125 A platen comprising the tubular lead body, the thin tight layer of soft rubber thereon, the tight winding of thin tough paper, and the covering of hard flexible material, such as the kangaroo skin, forms 130 a platen excellent in the many ways above

noted, while the general result is enhanced by the soft-rubber support of the same upon the platen axle.

Another feature of the lead body, especially when provided with the wrappings herein set forth, is that the action of the types upon the paper is substantially improved from their action in machines having platens of the standard type, namely, 10 shells of a tough compound of graphite, earth and rubber mounted upon wooden cores. As set forth in said Manning patent, the type-impressions upon such platens are not good, and it has always been supposed 15 that the trouble arose from the weakness and springiness of the type-bars. It has, however, been demonstrated that the abutment or stop-ring shown in the Manning patent can be omitted, and perfect type-impressions produced, by the use of the 20 tubular or hollow lead body, and without developing any of the faults which are set forth in said Manning patent, such as rapid wear of the types, and blurring or doubling 25 of the type-impressions. The lead body cooperates with the steel types and the springy type-bars in a perfect manner, producing excellent impressions, so that the noise of the types striking the Manning stop is entirely eliminated, while the noise of the 30 types striking the paper and platen is reduced practically to a negligible point. The type-bars may be made more narrow than usual, the original width being shown in 35 dotted line at 25, Figure 4. There is not only avoided the noise of the type-bars striking the usual abutment 26, but there is also effected a substantial economy in the 40 construction, assemblage and aligning of the type-bars in the machine. There is eliminated the noise of the type-bars striking the usual stop-ring 26, and moreover the 45 noise of the types striking the work-sheet is substantially reduced from the usual practice.

Another feature of improvement relates to the securing of detachable type-bars 24 in the machine in such a manner as to prevent shake of the type-bars at their pivots 50 when they are in printing positions.

When the type-bar 24 is in printing position, the open slot 27 in the hub of the type-bar is in horizontal position, thus giving opportunity for the type-bar to jar rearwardly at its lower end when in printing position. To minimize such undesirable play of the hub end of the type-bar, there 55 may be provided a curved or segmental rigid guard or bearing 28, which is detachably secured by screws 29 upon a segmental boss 30 provided upon the rear side of the type-bar segment 31. Whenever it is desired to take out a type-bar, said locking 60 segment 28 may be detached, then the type-bar may be taken out and another one sub-

stituted, whereupon the locking segment 28 may be returned to position. The exterior contour of the hooked pivoted portion 32 of the type-bar may be concentric with the type-bar pivot, and said contour may bear 70 against the segment 28, so that objectionable shake of the type-bar at its pivot may be precluded at the instant of printing.

The paper windings may be omitted or other material substituted therefor in some 75 cases, and other kinds of facing may be used for some purposes. The facing may be of tight helical windings 33 of strips of kangaroo skin or other thin, tough, hard, flexible material, Figure 5.

At Figure 3 is illustrated a sheet of kangaroo skin wrapped around the platen to form a durable facing therefor, the meeting edges of the wrapping being dovetailed 85 together at 34.

Variations may be resorted to within the scope of the invention, and portions of the improvements may be used without others.

Having thus described my invention, I 90 claim:

1. A cylindrical typewriter platen comprising a weighted self-sustaining tubular soft metal body, means for cushioning said body directly upon the platen axle, and a flexible durable covering for said body, said body 95 being nearly the full diameter of the finished platen.

2. A platen comprising a length of solid self-sustaining lead tube, soft rubber ends to support it directly upon the platen axle, 100 and a protective flexible sound-dulling impression-clearing covering upon said tube.

3. A platen comprising a length of lead tube, soft rubber ends to support it upon the platen axle, a protective flexible sound-dulling, impression-clearing covering upon said tube, bosses for the axle, said bosses having means to interlock with said ends, and means to connect the ends rotatively with the lead tube, said connecting means 105 comprising rubber hobs upon the ends to interlock with notches in the ends of the lead tube.

4. A platen comprising a length of lead tube, soft rubber ends to support it upon the platen axle, and a protective flexible sound-dulling impression-clearing covering upon said tube, said soft rubber platen ends being provided with perforations to conduct to the sound-deadening quality thereof. 110

5. A platen comprising a length of solid lead tube, soft rubber ends to support it upon the platen axle, and a protective flexible sound-dulling, impression-clearing covering upon said tube, said lead tube of sufficient weight to coat with the types to produce the required impressions upon the work-sheet. 115

6. A platen comprising a substantially inelastic solid tube of heavy plastic metal, said 120

4

tube self-sustaining under the type blows, a yielding support for said tube, and a wear-resisting sound-dulling facing for said tube.

7. A sound-dulling platen comprising a self-sustaining solid lead tube or pipe, soft cushioning means to support the same upon the platen axle, and a sound-dulling facing upon said tube to take the wear of the type, said tube being weighted or sufficiently heavy to be self-sustaining under the type blows and to serve by reason of its inertia to afford ample support for the work-sheet at the type blows, and being unprovided with a rigid internal supporting shell, and being bendable by the application of moderate force thereto.

8. A platen comprising a solid lead tube to form a weight substantially sufficient to withstand the blows of the types, a layer of thin highly-elastic soft rubber thereon, and a durable facing for said rubber.

9. A platen comprising a solid lead tube, cushioning means to support the same upon the platen axle, a highly tensioned winding of thin highly-elastic dental rubber on said tube, and a flexible durable facing upon said rubber.

10. A non-resonant platen provided with an axle and comprising a thick heavy body of solid lead tube or pipe, cushioning means supporting it upon the platen axle, a soft rubber layer upon said tube, and a durable flexible facing harder than the rubber.

11. A noise-dulling platen comprising a heavy lead pipe, cushions supporting the same, and an external layer upon the pipe comprising soft rubber, tough paper wound upon said rubber layer, and a protective facing for said paper.

12. A platen comprising a heavy lead body, a winding of soft rubber thereon, and a protective covering of kangaroo skin.

13. A sound-subduing platen comprising a lead tube or pipe forming a body, and means for preventing indentation of the lead by the types, comprising layers of rubber paper and kangaroo skin.

14. A platen comprising a lead tube, cushioning means to support the same upon the platen axle, a tensioned winding of thin highly-elastic dental rubber on said platen, and a flexible durable facing upon said rubber, said dental rubber interwound with windings of paper.

15. A platen comprising a length of lead tube, and a highly-elastic and impression-clearing layer thereon, comprising windings of rubber, paper and leather or skin facing.

16. A platen comprising a tubular lead body, a thin tight layer of soft rubber thereon, a tight winding of thin tough paper on the rubber, and a covering of hard flexible material.

BURNHAM C. STICKNEY.
